DISPLAY CASE FOR SAFETY RAZORS

Alan B. Lowry, Canton, Mass., assignor to The Gillette
Company, Boston, Mass., a corporation of Delaware

Filed Dec. 9, 1968, Ser. No. 14,856

Term of patent 14 years

Int. Cl. D9—04

U.S. Cl. D9—186

FIG. 1

FIG. 1 is a left side elevation of a display case for safety razors showing my new design;

FIG. 2 is a top plan view thereof; and

FIG. 3 is a right side elevation thereof.
The bottom of the case is plain.

I claim:

The ornamental design for a display case for safety razors, substantially as shown and described.
